(57) **CLAIM**

The ornamental design for an audio mixer, as shown and described.

DESCRIPTION

FIG. 1 is a front, top, right side perspective view of an audio mixer, showing our new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof; and,

FIG. 7 is a right side view thereof.

Evenly broken lines depict portions of the audio mixer which form no part of the claimed design.

1 Claim, 5 Drawing Sheets
